UNITED STATES PATENT OFFICE

2,155,462

WINDSHIELD CLEANER

John W. Anderson, Gary, Ind., assignor to Productive Inventions, Inc., Gary, Ind., a corporation of Indiana

Application September 28, 1935, Serial No. 42,652

4 Claims. (Cl. 15—118)

My invention belongs to the general class of cleaning devices, and relates more particularly to a device for cleaning windshields, windows and the like.

5 The present invention relates to certain improvements over my co-pending application filed March 16, 1935, Serial No. 11,392, and has among its objects the production of a device of the kind described that is simple, inexpensive, convenient, 10 durable, efficient and satisfactory for use wherever applicable. The same is especially adapted for use in garages, auto laundries, filling stations and the like for applying moisture to surfaces and at the same time removing dry or hardened 15 substances such as bugs or the like from the surface of windshields, and for removing water, snow and the like from surfaces. The same is likewise convenient for use in homes for cleaning windows, mirrors and like surfaces without 20 scratching of or injury to the surfaces to be cleaned.

The invention has among its further objects the production of a device of the kind described that is not affected by water and may be employed for 25 carrying the required amount of water to the surfaces to be cleaned and which will adjust itself to the surface cleaned so as to afford a uniform operation.

Many other objects and advantages of the construction herein shown and described will be obvious to those skilled in the art from the disclosure herein given.

To this end my invention consists in the novel construction, arrangement and combination of 30 parts herein shown and described, and more particularly pointed out in the claims.

In the drawing, wherein like reference characters indicate like or corresponding parts:

Fig. 1 is a view in elevation of one embodiment 35 of the invention, only a portion of the handle being shown;

Fig. 2 is substantially a sectional view taken on line 2—2 of Fig. 1;

Fig. 3 is a sectional view taken substantially on line 3—3 of Fig. 1; and

Fig. 4 is a sectional view taken substantially on line 4—4 of Fig. 1.

Referring to the drawing, 1 represents a recessed base member of resilient material such as rubber or the like provided with a squeegee head 2 at one edge formed integrally therewith and extending at an angle, as most clearly shown in Fig. 2. The base member 1 is provided with a reinforcement or stiffening member 3 seated in a recess and carries a moisture retaining and

applying member 4 of felt or the like, and the member 3 also provides means for securing the felt to the base member as well as to secure the abrasive member which is mounted in the felt. The stiffening member or plate 3 also affords a 5 means for rigidly securing the handle 5 to the body member, as will be hereinafter described.

As shown, the body member is provided with a squeegee head 2 extending at an angle to and connected to the body by a reduced flexible portion 7 so that the head may be flexed transversely of its longitudinal axis to a limited extent, the amount of flexing depending upon the pliability of the rubber as well as the thickness of the neck portion. It may be mentioned, however, that 10 the portion 7 has sufficient resistance that considerable pressure may be applied to the head for squeegeeing or wiping purposes to efficiently remove the moisture. The head is provided with the arrises or shoulders as indicated at 8 which 15 constitute a plurality of wiping edges. The stiffening plate 3 is preferably flanged as indicated at 10 and 11 and the body or base member 1 flanged thereover as indicated at 12 and 14 the two engaging near the bottom of the recess. It 20 will be noted that the flange 12 is undercut to a considerable extent so that the portion 13 of the flange engages the side of the flange 10 on the stiffening member. The flange 14 may be similarly constructed if desired, but for ease in assembling the undercut portion is shown omitted 25 on the flange 14 and the flange 11 doubled over as shown in the above mentioned figure. The edges of the plate are thus rubber covered and protected, and the parts interlocked.

The handle 5 is provided with a head or handle plate 17 connected thereto by the shank portion 18 projecting into the handle, 19 being a ferrule for reenforcing the handle and affording a more rigid construction. As shown, the plate 3 is punched out as indicated at 20 with a slight flange around each opening which may be threaded to engage with the screws 21 extending through the plate 17 and the body. The screws 21 rigidly and securely connect the handle, the body and plate 30 together.

As before mentioned, the plate 3 carries a moisture retaining pad 4 of felt or like material, the pad being retained in place between the flanges by means of the prongs 24 which are struck up 35 from the plate and extend through the pad and are thence bent over at their free ends to engage the pad. The pad is formed with a groove 22 extending from adjacent one end to adjacent the other end, the groove terminating in an aperture

23 at each end of the pad. Arranged in the groove 22 is an abrasive member preferably made in the form of a twisted rope made up of copper, bronze or like strands, the ends 25' of which extend through the apertures 23 to the ends of the pad. This abrasive strip is secured in place in the groove at the ends of the apertures by means of the prongs 26 which are struck up from the plate, the ends being bent over as indicated in Fig. 4. To facilitate bending of the free ends of the prongs 26, the pad may be slit as indicated at 27 adjacent each end.

In using the device, the pad being first saturated, the surface to be cleaned is rubbed with the 15 saturated pad 4, the mildly abrasive material 23 being drawn over the surface at the same time so as to remove any scum, specks, bug remnants or the like. After the surface has been moistened and washed by the pad and the foreign materials 20 loosened, the device is then drawn over the surface with the head 2 contacting with the surface, removing dirt and any excess moisture and in effect drying the surface. The device is particularly adapted for use in filling stations, 25 garages and the like for promptly removing dirt from a customer's windshield or car windows, without loss of time and without the use of chemicals which may injure the finish of the car or affect the glass. When so used, the device is usually 30 permitted to stand in the water so that the felt is at all times moist and more or less saturated with water, so that it is not necessary to take time to permit the same to soak up sufficient water for cleaning purposes.

35 It will be particularly noted that by employment of the stiffening plate, the squeegee, pad, abrasive and handle are all rigidly and securely connected together with the stiffening plate completely protected and covered so that no metal, 40 either from the plate or from the handle, can come in contact with the windshield or window glass, frame or body of the car and scratch the same. Likewise, the felt and abrading material are so connected to the handle that the same 45 cannot work loose and become ineffective. Obviously, the size of the device as well as the length of the handle may be made to suit the demands of the trade.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. A cleaning device comprising a substantially flat base member of resilient compressible material, said base member having an elongated

recess formed in one of its face portions, a stiffening plate positioned in said recess, said base member having inwardly extending portions adapted to overlie and cover the edges of said plate for securing the plate in said recess, and 5 a moisture retaining pad secured to said plate and extending outwardly from said recess beyond the adjacent face of said base member.

2. A cleaning device comprising a substantially flat base member of compressible resilient 10 material, said base member having an elongated recess formed in one of its face portions, an elongated stiffening plate having a laterally extending flange adjacent one of its longitudinal edges positioned in said recess, said base member 15 having an overhanging undercut portion forming an inwardly opening groove adjacent one of the longitudinal side portions of said recess for receiving the laterally extending flange on said plate, said base member having an inwardly extending portion along the opposite longitudinal side portion of said recess adapted to overlie the opposite longitudinal edge of said plate for concealing and securing the edges of said plate in 20 said recess, and a moisture retaining pad secured 25 to said plate and extending outwardly from said recess and beyond the adjacent face of said base member.

3. In a cleaning device of the kind described and in combination, a rubber backing member 30 having a recess formed in one side thereof, a metal reinforcing plate in said recess, portions on said member being adapted to overlie the edges of said plate, a felt pad disposed in said recess and secured to said plate, a handle having a base 35 plate positioned on the side of said backing member opposite said reinforcing plate, and readily removable securing means engaging said base plate and reinforcing plate for securing said plates and backing member together. 40

4. In a cleaning device of the kind described and in combination, an elongated rubber body member provided with a recess in one face thereof, a stiffening plate mounted in said recess and interlocking with the side walls thereof adjacent 45 the bottom of the recess, a felt pad provided with a recess in a face thereof terminating in apertures at the end of the pad, a strip of abrasive material provided in said recess with the ends extended through said apertures, said plate provided with prongs projecting through the pad and bent down to engage the same in the recess therein, and with prongs projected through the pad and bent back and overlying the abrasive strip adjacent the ends and below the outer face 55 of the pad, a handle, and means extending through the body member from the back side thereof for securing the handle and plate together.

JOHN W. ANDERSON. 60
